United States Patent Office

Des. 185,126
Patented May 12, 1959

185,126

ALPHABET FOR FORMING MONOGRAMS AND THE LIKE

Howard T. Brenner, Baltimore, Md., assignor to Samuel Kirk & Son, Inc., Baltimore, Md., a corporation of Maryland

Application July 22, 1958, Serial No. 51,898

Term of patent 14 years

(Cl. D64—17)

The figure on the drawing is a face view of an alphabet for forming monograms or the like showing my new design.

I claim:

The ornamental design for an alphabet for forming monograms or the like, as shown.
